UNITED STATES PATENT OFFICE.

JOHN H. VANCE, OF PITTSBURGH, PENNSYLVANIA, ASSIGNOR, BY DIRECT AND MESNE ASSIGNMENTS, TO TRU-WAY RAZOR COMPANY, OF PITTSBURGH, PENNSYLVANIA, A CORPORATION OF DELAWARE.

SAFETY RAZOR.

1,414,533.

Specification of Letters Patent. Patented May 2, 1922.

Application filed May 19, 1920. Serial No. 382,577.

To all whom it may concern:

Be it known that I, JOHN H. VANCE, a citizen of the United States, and resident of Pittsburgh, in the county of Allegheny and State of Pennsylvania, have invented a new and useful Improvement in a Safety Razor, of which the following is a specification.

This invention relates to a safety razor.

The object of the invention is to provide a safety razor the blade of which may be stropped or honed without being removed from the razor handle and without the use of special stropping appliances or attachments.

A further object of the invention is to provide a safety razor in which the blade is held securely in position, and in which all the parts may be readily assembled and disassembled.

In order to effect these objects, the razor embodies a special structure whereby the razor blade is held in position on the handle, and the guard rendered readily removable, the guard performing no function in holding the blade.

In the accompanying drawings Fig. 1 is a plan view of the razor; Fig. 2 is a side elevation of the razor with the guard removed; Fig. 3 is a plan view of the handle member of the razor; Fig. 4 is a side elevation of the handle member; Fig. 5 is a plan view of the blade locking bar; Fig. 6 is a central horizontal section through the locking bar; Fig. 7 is a bottom plan view thereof; Fig. 8 is a plan view of the razor guard; Fig. 9 is a central horizontal section through the guard; Fig. 10 is a cross sectional view through the guard taken on the line 10—10 Fig. 8; Fig. 11 is a cross sectional view through the locking bar taken on the line 11—11, Fig. 7; Fig. 12 is a cross sectional view through the handle member taken on the line 12—12, Fig. 3; and Fig. 13 is a longitudinal section on an enlarged scale taken on the line 13—13 Fig. 3.

The handle member of the razor comprises a handle portion proper 1, and a blade receiving portion 2. On the blade receiving portion 2 are posts 3 arranged to pass through corresponding orifices in the blade 4 of the razor. When in position on the blade receiving portion of the handle member, and fitted upon the posts 3, the razor blade is held in position by means of a locking bar 5.

The locking bar 5 has a flat, or slightly concave, under surface arranged to contact the razor blade, and is provided on its under surface with countersunk depressions 6 arranged to receive the posts 3 which pass through the razor blade. The locking bar 5 is held in position relatively to the razor blade 4 and the blade holding portion 2 of the handle member by engaging rigidly with the blade holding portion of the handle. The engaging means comprise a hook 7, which embraces the forward extremity of blade holding portion 2, and enters a suitable notch 8 in the blade holding member; and a pin 9 which projects upwardly adjacent the rearward extremity of the blade holding portion 2 and is arranged to enter a suitable orifice 10 in the under side of the locking bar 5. When so positioned, with the blade holding posts 3 engaging in countersunk depressions 6, hook 7 in the notch 8, and pin 9 in the orifice 10 of the locking bar; the locking bar is properly aligned and held relatively to the razor blade 4 and blade holding portion 2, but is not secured in such position.

In order that the locking bar may be secured, it is provided adjacent its rearward extremity with a catch member 11. The catch member 11 is resilient, being preferably formed by folding over a tongue stamped with the body of the locking bar. It is arranged so that its upper face is inclined rearwardly toward the handle 1 of the razor. Arranged to cooperate with the catch 11 of the locking bar is a slide member 12 on the handle 1. The member 12 is preferably of resilient material, and is slidably secured to the handle member by means of pins 13 which lie within longitudinal slots 14 in the member 12. At its forward extremity, member 12 is undercut on an angle to cooperate with catch 11 on the locking bar 5, and has adjacent such undercut portion 15, an upwardly extending knob or finger hold 16 for operation of the slide member.

With the locking bar 5 in position, as described above, the slide member is pressed forwardly so that its undercut portion engages with the catch 11 of the locking bar thus securing the parts relatively to each other. The resiliency both of the catch 11 and of the member 12 causes a firm locking engagement of the bars. When so locked the

edges of the blade 4 extend beyond both the blade holding portion 2 of the handle and the locking bar 5. The razor may thus be readily stropped or honed, and may, if so desired, be used as a simple razor without a safety guard.

In order to remove the locking bar 5 from position, so that the parts may be disassembled for cleaning of the blade or other purposes; the member 12 is slid rearwardly so that its undercut portion 15 is withdrawn thus releasing the catch 11 of the locking bar. The rearward extremity of the locking bar may then be lifted or dropped from the pin 10, and the hook 7 may be readily withdrawn from the notch 8.

When it is desired to utilize the razor of the present invention as a safety razor, a suitable guard 17 is added to the assembly of parts previously described. This guard 17 is provided at its forward extremity with a pair of hooked tongues 18 which engage in corresponding grooves 19 on the under side of the locking bar 5. At its rearward extremity, the guard has a tongue 20 which engages under the lip 21 of the catch 11 on the locking bar. In order to assure an accurate alignment of the guard 17 relatively to the other parts of the razor, it is provided with a downwardly offset portion 22 extending longitudinally of the bar, which engages in a corresponding groove 23 in the upper surface of locking bar 5. In order that the guard 17 may be readily removed from the locking bar, it is provided with an upturned thumb piece 24 against which pressure may be exerted to slide the guard out of its engaging position.

It is to be noted that the guard of the razor is entirely an added member, and that it performs no function in the razor assembly other than that of a mere guard, the blade being held entirely by the handle parts and the locking bar. The guard may thus be removed and leave the blade firmly secured in position in the body of the razor. For this reason, the blade of the razor may be stropped or honed while in position in the body of the razor itself and the use of a special stropping handle, or of special stropping appliances is rendered unnecessary. The guard may thus be removed and the razor blade conveniently stropped or honed during the operation of shaving. This is a feature peculiar to the safety razor of the present invention.

The handle member proper of the razor is

shown as straight, but may, if so desired, be made of the balanced type without modifications in the other portions of the device. 60 This straight handle is preferably provided at its extremity with a cupped finger grip 25, and is knurled throughout to provide a surface which may be firmly grasped.

The razor handle member, locking bar, and guard may be made of any material found suitable in use. It is preferable however, that such parts be stamped from metal because of manufacturing economy, and to secure the requisite resiliency and durability 70 of the parts.

As the device is susceptible of a number of modifications without departing from the spirit of the invention, no limitations, other than those contained in the appended claims, 75 are to be imposed upon the scope of the invention.

What I claim is:

1. A safety razor comprising mutually fixed handle and blade holding members, a locking bar arranged to engage on said blade holding member and secure a blade thereto and having notches on the under surface of its forward end, a lip on the locking bar adjacent the rear end thereof, and an independently removable guard member having hooks arranged to engage in the notches in said locking bar and a tongue arranged to engage under said lip. 80

2. A safety razor comprising mutually fixed handle and blade holding members, said blade holding member having a notch on the under side of the forward end thereof, a locking bar arranged to secure a blade on said blade holding member and having a hook engaging in the notch in said blade holding member and having notches in the under side of the forward end thereof, a member extending longitudinally of said handle member and slidable thereon arranged to engage the rear end of said locking bar, a lip on the locking bar adjacent the rear end thereof, and an independently removable guard member having hooks arranged to engage in the notches in said locking bar and a tongue arranged to engage under said lip. 90

In witness whereof, I hereunto set my hand.

JOHN H. VANCE.
